UNITED STATES PATENT OFFICE

DAVID D. McCLUNEY, CHESTER L. McCLUNEY, AND HERBERT C. McCLUNEY, OF LOS ANGELES, CALIFORNIA

DESIGN FOR A VENTILATOR

Application filed December 24, 1930. Serial No. 38,114. Term of patent 14 years.

To all whom it may concern:

Be it known that we, DAVID D. McCLUNEY, CHESTER L. McCLUNEY, and HERBERT C. McCLUNEY, citizens of the United States, residing in the city of Los Angeles, in the county of Los Angeles and State of California, have invented a new, original, and ornamental Design for Ventilators, of which the following is a specification, reference being had to the accompanying drawings, forming a part thereof.

We claim:

The ornamental design for a ventilator, as shown.

DAVID D. McCLUNEY.
